UNITED STATES PATENT OFFICE.

HENRY CURTIN, OF LITTLE FALLS, NEW YORK.

THREAD-GUIDING DEVICE FOR KNITTING-MACHINES.

SPECIFICATION forming part of Letters Patent No. 412,475, dated October 8, 1889.

Application filed January 23, 1889. Serial No. 297,269. (No model.)

To all whom it may concern:

Be it known that I, HENRY CURTIN, of Little Falls, in the county of Herkimer, in the State of New York, have invented new and useful 5 Improvements in Thread-Guiding Devices for Knitting-Machines, of which the following, taken in connection with the accompanying drawings, is a full, clear, and exact description.

10 This invention consists, first, in a novel construction of a thread-guide designed to be used in connection with reciprocating needles of a knitting-machine, and which is simple, efficient, and durable in its operation, and, 15 secondly, in a novel adjustable support for said thread-guide, all as hereinafter more fully described, and specifically set forth in the claims.

In the annexed drawings, Figure 1 is a side 20 elevation of a knitting-machine equipped with my improved thread-guide. Fig. 2 is a top plan view of the same. Fig. 3 is an enlarged vertical transverse section of one side of the needle-cylinder with my improved 25 thread-guide, illustrating the adjustability of the latter; and Fig. 4 is a detached perspective view of one of the thread-guides.

Similar letters of reference indicate corresponding parts.

30 A represents the rotary needle-cylinder, which is of the usual and well-known form and pertains to the class of knitting-machines in which the needles *c c* are reciprocated vertically between sinkers *d d*, fixed to the needle-cylinder, and are provided with latches for closing the hooks of the needles as they descend through the loops of yarn previously formed on the needles.

R represents a ring, which is sustained in a 40 horizontal position at the outside of the needle-cylinder, preferably by means of brackets *B B*, which are provided with vertical slots *e*, and are secured vertically adjustably to the exterior of the upper cam-ring *P* by bolts *e'*, passing through the said slots and into the aforesaid cam-ring. Said adjustable attachment of the aforesaid brackets allows the ring *R* to be raised or lowered, as may be required to bring the thread-guides into proper position 45 in relation to the top of the needle-cylinder. The cam-ring *P*, I prefer to divide into two

semicircular sections *P⁸* and *P⁹*, as described in another application for Letters Patent, Serial No. 296,960, filed by me January 21, 1889.

In order to facilitate the attachment and 55 detachment of the ring *R*, I divide the same also transversely directly over the joints of the cam-ring sections into two semicircular sections, each of which I support independently of the other by attaching to each section of the cam-ring *P* a sufficient number of brackets *B B* to support one of the sections of the ring *R*. I am thus enabled to remove either of the cam-ring sections without disturbing the attachments of the ring-sections *R*. 60 The upper ends of the brackets are provided with eyes *f*, through which the ring-sections *R* pass, and set-screws *f'*, connected to said eyes and engaging the ring, hold the latter in place. 70

On the ring *R*, I mount the thread-guides, which consist of brackets *C C*, distributed around the needle-cylinder, as shown by full lines and dotted lines in Fig. 2 of the drawings. Each of said brackets is formed with 75 an eye *b'*, by which it is mounted on the ring *R*, and in order to allow the bracket *C* to be tilted toward or from the needle-cylinder, and thus adjust the thread-guide in its position in relation to the path of the needles, I form the 80 ring *R*, which constitutes the thread-guide support, of a round bar or bar of circular form in cross-section of its body, and also form the eye *b'* of circular shape and of a diameter to neatly fit the ring. A set-screw *b*, 85 inserted transversely into the eye *b'* and engaging the ring *R*, retains the bracket *C* in its adjusted position. Said bracket is also formed with two lugs *C'* and *C''*, which are perforated in line with each other and in a line radially 90 to the needle-cylinder. The perforation of the lug *C'* is of a diameter to permit a tube *t* to be inserted, which tube is retained therein by a set-screw *u*, passing transversely through the top of the lug and engaging the tube. 95

In order to render the tube more durable, I form the same of glass or suitable vitrified mineral.

The bracket *C* is furthermore formed with an outwardly-extended arm *a*, which is slotted 100 or provided with a passage, through which the thread runs, and from which the thread

passes through the perforation of the lug C'', and thence through the tube *t* to the needle-cylinder.

Having described my invention, what I claim
5 as new, and desire to secure by Letters Patent,
is—

1. In combination with the needle-cylinder, a thread-guide support of circular form in cross-section of its body sustained at the outside of the needle-cylinder, a bracket provided with a corresponding circular eye and mounted thereby on the aforesaid support and adapted to turn thereon toward and from the needle-cylinder, and a set-screw clamping the thread-guide in its position, substantially 15 as described and shown.

2. In combination with the needle-cylinder and reciprocating needles, the bracket C, formed with the lugs C' C'', perforated in line 20 with each other, the tube *t*, inserted in the lug C', the set-screw *u*, retaining the tube in the lug, and the arm *a*, extending from the

bracket and provided with a passage through which the thread runs, as set forth and shown.

3. In combination with the needle-cylinder 25 and reciprocating needles, the ring R, of circular form in cross-section of its body, sustained at the outside of and concentric with the needle-cylinder, brackets C C, provided, respectively, with a circular eye *b'*, and mounted 30 thereby on the aforesaid ring, set-screws *b* *b*, attached to the brackets and engaging the ring, and tubes *tt* on the brackets and having their inner ends over the path of the needles, substantially as described and shown.

In testimony whereof I have hereunto signed my name, in the presence of two witnesses, at Little Falls, in the county of Herkimer, in the State of New York, this 15th day of January, 1889.

HENRY CURTIN. [L. S.]
